(57) **CLAIM**

The ornamental design for a deck plank positioning measurement tool, as shown and described.

DESCRIPTION

FIG. 1 is a top and front perspective view of a deck plank positioning measurement tool showing my new design;

FIG. 2 is a bottom and front perspective view of the deck plank positioning measurement tool;

FIG. 3 is a top plan view of the deck plank positioning measurement tool; and,

FIG. 4 is a front plan view of the deck plank positioning measurement tool.

The broken line showing of instructional writing is included for the purpose of illustrating non-claimed subject matter and forms no part of the claimed design.

1 Claim, 4 Drawing Sheets
